UNITED STATES PATENT OFFICE.

WARREN D. HOUSE, OF KANSAS CITY, MISSOURI, ASSIGNOR, BY MESNE ASSIGNMENTS, TO THE HOUSE IMPROVED TELEPHONE COMPANY, OF PHILADELPHIA, PENNSYLVANIA.

TELEPHONE.

SPECIFICATION forming part of Letters Patent No. 358,812, dated March 1, 1887.

Application filed December 8, 1886. Serial No. 221,001. (No model.)

To all whom it may concern:

Be it known that I, WARREN D. HOUSE, a citizen of the United States, residing at Kansas City, in the county of Jackson and State of Missouri, have invented certain new and useful Improvements in Telephones; and I do hereby declare the following to be a full, clear, and exact description of the invention, such as will enable others skilled in the art to which it applies to make and use the same.

The object of my invention is to furnish a new and improved apparatus for electrically transmitting and receiving articulate speech and other sounds between distant stations.

It consists, broadly, in causing electric currents, produced at the transmitter by the sounds to be conveyed, to set up molecular vibrations in an electrolytic vibratory body located at the receiving-station, which vibrations, imparted to the surrounding air, reproduce the original sounds.

In the accompanying drawings I have illustrated means for practicing the invention.

Figure 1 represents diagrammatically two stations provided with means for intercommunication in accordance with the principles of my invention. Fig. 2 represents a modified form of the receivers shown in Fig. 1.

Similar letters of reference indicate similar parts.

X and Y indicate two distant stations, each of which I have shown as provided with a transmitting and receiving instrument for intercommunication. As illustrated, the line-wire S is grounded at each end, and is in circuit with the secondary coils of the transmitter induction-coils B B', and with the primary coils of the receiver induction-coils C C'.

The transmitters, which may be of any kind adapted to receive the sound-vibrations and transform them into corresponding electrical energy, are connected up with the primary coils of the induction-coils B B', and the receivers with the secondary coils of the induction-coils C C'.

In the drawings I have illustrated different modifications in the construction of the receiver, all of which come within the purview of my invention.

In the form represented at the lower left-hand corner of Fig. 1, A indicates a suitable basal support, upon which rests a plate, D, preferably of carbon. Upon this carbon plate D is superimposed a block or body, E, composed of or saturated or impregnated with electrolytic material. Contact between the plate D and block E throughout their contiguous surfaces is made as intimate as possible, and is preferably secured either by carefully smoothing said surfaces and joining them by screws or otherwise, or by molding and compressing the material composing the electrolytic body upon the plate.

By the expression "electrolytic material," as employed throughout this specification, I intend all such substances, liquid or solid, which, as component parts of the block or body E or its equivalent, will be decomposed by the passage of the electric current.

Thus I have found that pulverized carbon and phosphate of sodium intimately mixed in a dry or moist condition and formed into the shape of a block will give good results, the percentage of carbon employed being so chosen as to give conductivity to the block, but not sufficient in quantity to prevent electrolytic action during the passage of the currents. A block of plaster-of-paris that has been compressed to give it stability and then saturated with an aqueous solution may also be employed. For this purpose I may employ a solution of phosphate of sodium, sal-ammoniac, muriatic acid, or even water alone. I may also employ for the material composing the block any conducting substance containing an electrolyte, provided the same is saturated with oil or its equivalent in such proportion as to decrease the conductivity of the conducting substance to an extent permitting the decomposition of the electrolyte during the passage of the currents.

The plate D may be of platinum or the like, if desired. Carbon, however, is preferable on account of its cheapness, while over the baser metals it possesses the advantage of non-corrodibility.

When a saturated block is employed, the saturated condition is maintained, preferably,

by capillary attraction, as hereinafter described, or by inclosing it within an air-tight receptacle for the purpose of preventing evaporation, and, if desired, a saturated sponge 5 may be inclosed within the receptacle to maintain the humidity of the air therein.

To the basal support A is connected a yoke, as shown, having a cross-piece, G, provided with a threaded perforation, within which engages the externally-threaded sleeve H. An electrode, L, passes through this sleeve, and is provided with a collar, f, against which the sleeve is adapted to bear. At its lower extremity the electrode L is provided with a bent radial arm, M, to whose under surface is connected the spring N, composed of or tipped at its contact point with the block E with, preferably, platinum or nickel. Silver, copper, German silver, and other metals also 20 give good results, but should be first amalgamated with mercury to resist corrosion.

The electrode L is provided with means for rotating it within the sleeve H, such means consisting of the crank arm T, or suitable gearing connected with a suitable source of power, regulated, if desired, by clock-work mechanism or the like, so as to insure a uniform movement.

The carbon electrode D and the electrode L 30 are connected in the receiver circuit through the intermediacy of the block E, and a battery, as R, is interposed in the receiver-circuit, so as to maintain a constant state of polarization between the block and the contact 35 of the electrode L. The electrode L may be connected with either pole of the battery, although I have obtained the best results by connecting it to the zinc pole, the electrode D being of course connected with the opposite 40 pole. The strength of the polarizing battery should, preferably, be equal to the maximum strength of the induced currents in the receiving-circuit. It will be readily understood, however, that the employment of a polarizing-battery, while desirable for the reasons stated, 45 is not absolutely essential to the operation.

The pressure of the spring-contact upon the block E being regulated by means of the sleeve H and regulating tension-screw g, so as to insure a rubbing contact between the block and metallic tip, the electrode L is rotated within the sleeve H during the passage of the transmitting-currents over the line-wire S and receiving-circuit, the tip of the spring-contact 55 moving over the surface of the block. The passage of the induced currents in the receiving-circuit during this operation decomposes the electrolytic material at the moving contact-point, thereby causing molecular vibrations, which, being communicated to the air, 60 reproduce the sounds operating upon the transmitter.

When a line of high resistance is being operated upon, I preferably interpose a rheostat 65 in the receiving-circuit, in addition to the polarizing-battery.

The receiver may in some instances be connected up in direct circuit with the transmitter, or in any other familiar manner, or may be operated by magneto-currents or earth-currents, or by means of a static current produced, for instance, by means of a condenser. The line-wire, moreover, need not necessarily be grounded, in which event it operates as a condenser.

In the form of receiver illustrated in Fig. 2 75 I have shown a means for maintaining the saturation of the electrolytic material by capillary attraction. In this instance the block E' and its carbon electrode D' rest upon a receptacle, 80 T, of porous or absorbent material—such as plaster-of-paris or the like—preferably shellaced or varnished upon its exterior sides and bottom and inclosed within a suitable casing, V.

The saturating solution is contained within 85 the receptacle T, and is conveyed by capillary attraction to the plate D' and block E' above it. In connection with this figure I have also illustrated gearing H', for operating the rotary electrode L.

Although I have secured the best results by imparting motion to the electrode L or L', the receiver will operate while the contact is stationary. A form of receiver especially adapted for this use is illustrated at the lower right-hand portion of Fig. 1. In this instance the electrode L² is provided with a regulating-screw, n, for securing the proper degree of pressure or contact with the electrolytic disk E'. The disk in this case is kept at the point 100 of saturation by means of the porous receptacle T, upon which it rests, said receptacle containing the saturating solution. The electrolytic material is connected with an electrode located between it and the receiver-opening, 105 corresponding to the electrodes D D', hereinbefore described. The vibrations imparted to the air, consequent upon molecular disturbance during the transmission of speech, are concentrated and rendered audible even where 110 the vibrations are comparatively slight.

In the forms of receiver illustrated in Fig. 2 and at the left hand of Fig. 1 the effects may be increased by mounting the receivers upon a sounding-board.

I am aware that it has been heretofore proposed to construct a receiver having as one electrode various kinds of animal tissue containing electrolytic material in contact with an opposite resonant metallic electrode. The animal tissue as therein employed is, however, not adapted to be set into molecular vibration by the electrolytic action, thereby differing essentially from my invention.

I am also aware that a receiver has been 125 proposed wherein a diaphragm provided with a spring projection pressing upon a revolving roller of material soaked in an electrolytic solution, and thereby normally restrained, is released and subjected to flexure by the electrolytic action of the current between the said 130 spring and moving roller. It is obvious that

this also differs widely in principle of operation from my invention.

Having thus described my invention, what I claim, and desire to secure by Letters Patent, is—

- 5 1. A telephone-receiver provided with a body of vibratory electrolytic material and an opposite electrode in contact therewith, substantially as described.
- 10 2. A telephone-receiver provided with a body of vibratory electrolytic material and an opposite electrode in contact therewith, and means for moving the two relatively to each other, substantially as described.
- 15 3. A telephone-receiver provided with a body of vibratory electrolytic material, an opposite electrode having a spring-contact with said body, and means for rotating the electrode, substantially as described.
- 20 4. A telephone-receiver provided with a body of vibratory electrolytic material, an opposite electrode having a bent radial arm and adjustable spring-contact, and means for rotating the electrode, substantially as described.
- 25 5. A telephone-receiver provided with a body of vibratory electrolytic material, an electrode attached thereto, and an opposite electrode in contact with said electrolytic material, substantially as described.
- 30 6. A telephone-receiver provided with a body of vibratory electrolytic material and a receptacle containing a saturating solution and having porous walls, substantially as described.
- 35 7. A telephone-receiver provided with a body of vibratory electrolytic material, a receptacle containing a saturating solution and having porous walls, and an intermediate porous electrode, substantially as described.
- 40 8. A telephone system consisting of an induction-coil, a transmitter connected with the primary circuit of said coil, a line-wire connected with the secondary circuit of said coil, a receiving induction-coil having its primary circuit connected with the line-wire, and a receiver connected with the secondary circuit of said coil, the receiving-circuit including a polarizing battery and the receiver having a vibratory body of electrolytic material and an opposite electrode in connection therewith, substantially as described.
- 45 45
- 50 50

In testimony whereof I affix my signature in presence of two witnesses.

WARREN D. HOUSE.
